(No Model.)

J. SWEGLES.
CATTLE GUARD.

No. 429,393.

Patented June 3, 1890.

下印 1

The diagram illustrates a mechanical linkage mechanism. A fixed horizontal base is shown at the bottom. A vertical rod, labeled *J*, is attached to the base. A horizontal connecting rod, labeled *G*, is hinged to the vertical rod *J*. The free end of the connecting rod *G* is hinged to a horizontal beam, labeled *H*, which is inclined at an angle. A horizontal force, labeled *F*, is applied to the beam *H* at a point indicated by a vertical line. The beam *H* is hinged to a horizontal frame, labeled *B*, which is inclined at a different angle. A horizontal force, labeled *T*, is applied to the frame *B* at a point indicated by a vertical line. The frame *B* is supported by a vertical leg, labeled *C*, which is in contact with the base. A horizontal force, labeled *D*, is applied to the leg *C* at a point indicated by a vertical line. The frame *B* is also supported by a vertical leg, labeled *E*, which is in contact with the base. A horizontal force, labeled *F*, is applied to the leg *E* at a point indicated by a vertical line. The frame *B* is supported by a vertical leg, labeled *F*, which is in contact with the base. A horizontal force, labeled *T*, is applied to the leg *F* at a point indicated by a vertical line. The frame *B* is supported by a vertical leg, labeled *G*, which is in contact with the base. A horizontal force, labeled *F*, is applied to the leg *G* at a point indicated by a vertical line. The frame *B* is supported by a vertical leg, labeled *H*, which is in contact with the base. A horizontal force, labeled *T*, is applied to the leg *H* at a point indicated by a vertical line. The frame *B* is supported by a vertical leg, labeled *I*, which is in contact with the base. A horizontal force, labeled *F*, is applied to the leg *I* at a point indicated by a vertical line. The frame *B* is supported by a vertical leg, labeled *J*, which is in contact with the base. A horizontal force, labeled *T*, is applied to the leg *J* at a point indicated by a vertical line. The frame *B* is supported by a vertical leg, labeled *K*, which is in contact with the base. A horizontal force, labeled *F*, is applied to the leg *K* at a point indicated by a vertical line.

UNITED STATES PATENT OFFICE.

JOHN SWEGLES, OF WAYNE, MICHIGAN.

CATTLE-GUARD.

SPECIFICATION forming part of Letters Patent No. 429,393, dated June 3, 1890.

Application filed February 25, 1890. Serial No. 342,160. (No model.)

To all whom it may concern:

Be it known that I, JOHN SWEGLES, a citizen of the United States, residing at Wayne, in the county of Wayne and State of Michigan, 5 have invented certain new and useful Improvements in Cattle-Guards, of which the following is a specification, reference being had therein to the accompanying drawings.

This invention relates to new and useful improvements in railway-surface cattle-guards; and the invention consists in the peculiar construction of movable gates or platforms arranged in the track normally horizontal, and so arranged that when an animal steps 10 upon one end thereof a gate or platform is thrown up across the track, which is free to fall back again as soon as the animal withdraws; and, further, in the peculiar construction, combination, and arrangement of the 15 various parts, all as more fully hereinafter described.

In the drawings accompanying this specification, Figure 1 is a plan view. Fig. 2 is a side elevation showing the guard raised, and 20 Fig. 3 is a vertical central view through the guard as lowered.

Are the rails of the railroad-track to which my device is applied. I show it as applied only between the rails; but it is evident that 25 similar devices may be applied upon each side of the track, between the track and the fences.

B is a movable platform, of a width slightly less than the distance between the rails, and 30 pivotally supported upon suitable brackets C, secured upon the tie, and corresponding brackets D upon the platform. This platform is preferably balanced, or nearly so, and at its inner end is provided with a curved arm 35 E, which has the upward bend F and terminates in a downwardly-projecting arm G.

H is a gate or guard-platform, having the arms I at its inner end, which engage with a suitable shaft J, supported in the brackets 40 K, resting upon the tie in the track. The

outer end of the gate H is supported parallel with the track by means of the bracket L.

M is a downwardly-projecting arm secured centrally to the inner edge of the gate H and provided with an aperture N, in which the 50 arm G of the lever E engages, the bend F of this lever bearing upon the shaft J.

The parts being thus constructed, they are intended to be operated as follows: The normal position is shown in Fig. 3, in which 55 position the platforms rest parallel with the rails, the platform B being next to the road. As the cattle in attempting to cross step upon one end of the platform their weight will depress it, raising the inner end, and with it the 60 arm E, which, acting through the arm G, engages with the arm M of the gate H and raises the gate to the position shown in Fig. 2, forming an apparent barrier to the passage 65 of the animal. As soon as the animal retreats the gate by gravity will fall to its normal position, and thus leave the track free for the passage of the trains.

What I claim as my invention is—

1. In a railway cattle-guard, the combination of the centrally-pivoted platform and the vertically-moving gate pivoted at the end of the platform, the downwardly-curved arm on the platform engaging a depending bracket upon the gate, substantially as described. 70

2. In a railway cattle-guard, the combination of the platform B, centrally pivotally supported, the gate H, having arms I pivoted upon the shaft J, and the apertured arm M, the curved lever E upon the platform, having bend F and arm G, and the bracket L, substantially as described. 75

In testimony whereof I affix my signature, in presence of two witnesses, this 15th day of February, 1890.

JOHN SWEGLES.
